ELECTROSURGICAL APPARATUS

Rolland H. Maxson, Milton, Wis., assignor to
 The Burdick Corporation, Milton, Wis., a corporation of Delaware

Application April 15, 1933, Serial No. 666,297

15 Claims. (Cl. 174—177)

My invention relates to electro-surgical apparatus; more particularly to what may be termed an electro-surgical knife for severing or "cutting" tissue, etc. in connection with surgical operations.

5 High frequency currents have heretofore been employed in surgery with considerable success. Such currents produced by spark gap oscillator circuits and comprising damped waves are particularly effective in producing coagulating effects 10 upon or within tissues adjacent the active electrode. On the other hand, high frequency currents produced by vacuum or radio tube oscillator circuits and comprising undamped waves are particularly effective in severing or "cutting" tissue 15 at the active electrode. One of the principal difficulties or disadvantages inherent in the use of damped wave high frequency (spark gap oscillator) currents in surgery is that the severance of tissue is so slow that the necessarily prolonged 20 application of heat results in injurious dessication or dehydration of tissue and consequent delay and other complications in healing. On the other hand, the use of undamped wave high frequency (vacuum tube oscillator) currents effects such 25 rapid cutting and so little coagulation that excessive bleeding may occur at an incision.

Heretofore, therefore, the use of high frequency currents in acusection has been limited to situations where relatively little cutting was required— 30 making feasible the employment of spark gap oscillator (damped wave) currents—or where relatively little bleeding was to be expected—making feasible the employment of vacuum tube oscillator (undamped wave) currents—or to instances where it was possible first to apply an 35 electrode supplying cutting (undamped wave) current and then immediately to follow with an electrode supplying coagulating (damped wave) current. The limitations of either type of high 40 frequency current and the danger and additional time required for sequential application of both types of current have constituted serious obstacles to the extension of electro-surgical technique, even though conditions might otherwise indicate 45 the desirability of this form of therapy.

One of the objects of my invention is to provide electro-surgical equipment which combines the advantages of both undamped wave and damped wave currents for surgical technique.

50 Another object is to provide apparatus whereby a single active electrode may possess simultaneously both the attributes of rapid cutting and effective coagulation.

55 Another object is to provide equipment which will deliver to a common active electrode electri-

cal energy which is a resultant derived from electrical energy components of both damped and undamped wave type.

Another object is to provide apparatus whereby either cutting or coagulating or combined cutting and coagulating currents may be applied to a single active electrode at the will of the operator.

Another object is to provide apparatus which is simple, effective and reliable for accomplishing the intended results.

Other objects and advantages will hereinafter appear.

In general, in accordance with my invention, I propose to combine or "mix" currents constituting or made up of damped and undamped waves and thereby produce a current which is a resultant of the fundamental damped and undamped wave components and which possesses the property of effecting, apparently simultaneously, both cutting and coagulating effects. I also make provision for the selective application to an active electrode of either damped or undamped wave trains (i. e. of the fundamental components) or a combination or resultant of both so as to enable the operator to emphasize, at will, either a cutting characteristic or a coagulating characteristic or to obtain both of these characteristics apparently simultaneously.

The accompanying drawing illustrates a typical circuit and arrangement of apparatus for carrying my invention into effect.

Referring to the drawing, the equipment comprises in general a suitable spark gap oscillator A for producing electrical energy of damped wave high frequency oscillating current type, a suitable vacuum tube oscillator B for producing electrical energy of undamped wave high frequency oscillating current type, an impedance coupling transformer C to which both oscillators and the necessary electrode or applicator may be connected, and a control switch D for selectively bringing into action either oscillator alone or both oscillators simultaneously to govern the type of current delivered to the active electrode.

The spark gap oscillator A comprises a step-up iron core transformer 5 having a primary winding 6 and a secondary winding 7, an inductance coil 8, a suitable spark gap 9 and a ground or neutral connection through a condenser 10. The input of the spark gap oscillator A is supplied with electrical energy from the service line of ordinary alternating current (say 60 cycle, 110 volt). The input energy is applied to the transformer primary through a control switch 11 and

conductors 12 and 13. The secondary or high frequency high voltage side of the spark gap oscillator is connected to the impedance coupling transformer C by conductors 14 and 15.

5 The vacuum tube oscillator includes an iron core step-up transformer 20 having a primary winding 21 and a secondary winding 22, a vacuum tube 23 of the three electrode type and an inductance coil 24. The grid 25 of the vacuum tube is connected to one end of coil 24 through a conductor 26, a resistance 27 and condenser 28 which are in parallel, and a conductor 29. The oscillating or "tank" circuit comprises inductance coil 24, conductors 29 and 31, condenser 30 and 10 conductor 32.

15 The plate 35 of the vacuum tube is connected to one terminal of the secondary 22 of transformer 20 through an inductance 36 and conductors 37 and 38 and to one terminal of coil 24 (and consequently to the oscillating circuit) through a condenser 39 and conductors 40 and 41. The filament 42 of the vacuum tube is connected by conductors 43 and 44 to the secondary winding 45 a relatively small low voltage transformer 46, which transformer has a primary winding 47. The mid-point of secondary 45 is connected by conductors 48 and 49 to a terminal of the secondary of transformer 20, to a point on induction coil 24 and to a point between a pair 20 of condensers 50 and 51 which are bridged between conductors 43 and 44.

25 The primary winding 21 and the primary winding 47 are connected to feed conductors 52 and 53 through an adjustable switch 54 and a variable resistance 55 respectively. The switch 54 controls the input to the vacuum oscillator.

30 One terminal of impedance coupling transformer C is connected to coil 24 through conductor 55, a fixed condenser 56 and a variable condenser 57. The other terminal of transformer C is connected to coil 24 through a conductor 58.

35 The two service terminals 60 and 61 of the apparatus are connected to impedance coupling transformer C by conductors 62 and 63 respectively. These terminals are for the connection of the two applicators or electrodes 64 and 65, by means of which the high frequency current is applied to the patient,—the "ground" electrode 64 generally consisting of a plate of considerable 40 size upon which the body of the patient lies and the active electrode 65 consisting of a wire or applicator of any desired type and shape depending upon the character and location of the operation to be performed.

45 Thus the oscillator A is provided with an output circuit which includes coil C between conductors 62 and 63, and the conductors 62 and 63, and which is adapted to energize the service terminals 60 and 61. The oscillator B is provided 50 with an output circuit including coil 24 between the conductors 55 and 58, conductors 58 and 62, conductor 55 with the condensers 56 and 57 therein, coil C between conductors 55 and 63, and conductor 63. That output circuit of the oscillator B is also adapted to energize the service terminals 60 and 61. In other words, the output circuits just described are connected in parallel to each other and both are connected to the service terminals 60 and 61, which may be connected 55 as illustrated in the drawing to the electrodes 64 and 65, respectively, to provide an applicator circuit.

60 It will be seen from the foregoing that the oscillator output circuits may be referred to as parallel connected branches of a circuit including an

applicator branch electrically connected and common to the parallel connected branches. Thus, output circuits or branches being arranged to supply energy to the applicator circuit or branch may be considered as sources of energy or as oscillators, which, like the output circuits or branches, are connected in parallel.

5

65 The control switch D, which preferably may be actuated by the foot of the operator, includes a movable spark gap oscillator control contact 70, a movable vacuum tube oscillator control contact 71 and a combined oscillator control contact 73. Contacts 70, 71 and 72 are connected to one side of the service mains 13, the other side being connected to conductors 13 and 52. A suitable line 10 switch 74 may be interposed between the source of power and the control switch.

10

15 The impedance of the spark gap oscillator circuit should be relatively low as compared to that of the vacuum tube oscillating circuit and that of the output circuit (i. e., the circuit including the electrodes and the patient's body); and the impedance of the vacuum tube oscillating circuit should be high as compared to the impedance of the output circuit. This relationship will permit each oscillator to feed current properly to the output or patient's circuit without feeding, at least to an objectionable degree, into the other oscillator. The amount of the current delivered to the output circuit of the spark gap oscillator 20 may be varied to give the desired intensity at the active electrode by adjusting the spark gap or the input control switch 11. The amount of current delivered to the output circuit by the vacuum tube oscillator may be varied by adjusting the variable condenser 57 or the input control switch 54.

25

30 When it is desired to apply only damped wave current, switch 70 is closed, completing a circuit from the power main to the spark gap oscillator. 40 Upon the closure of this switch high frequency damped oscillating current is delivered to the active electrode 65. If it is desired to apply only vacuum tube oscillator current, switch 71 is closed, completing a circuit to the vacuum tube 45 oscillator. Upon the closing of this switch high frequency undamped oscillations are delivered to the active electrode. In the event that it is desired to utilize simultaneously currents of both damped and undamped wave characteristics, 50 switch 72 is closed whereupon circuits are completed from the power line to both oscillators. Upon the closing of this switch the current delivered to the active electrode is a resultant of the fundamental components, i. e., of the damped 55 and undamped waves.

55

60 Having thus explained and illustrated the nature and an embodiment of my invention, what I claim and desire to secure by United States Letters Patent is as follows:

60

65 1. An electro-surgical apparatus comprising an oscillator for producing damped current waves, an oscillator for producing undamped current waves, an applicator circuit, and a transformer having a common terminal with each said oscillator and said applicator circuit and having a terminal for each said oscillator and for said applicator circuit at potentials different from the potential of said common terminal.

65

70 2. In an electro-surgical apparatus including a pair of oscillators capable of producing damped and undamped electrical oscillations, the combination of an applicator electrically associated with both oscillators for deriving energy therefrom, with means in the output from each said 75

oscillator electrically associated with said applicator for maintaining a predetermined ratio between the amounts of energy derived from said oscillators by said applicator, and means for selectively varying the ratio.

3. An electro-surgical apparatus comprising a damped-wave current oscillator, an applicator circuit, a coil interposed between said oscillator and said applicator circuit for inducing energy into said applicator circuit, an undamped-wave current oscillator electrically connected across the terminals of said coil, and switches whereby a source of current may be selectively connected separately to either and simultaneously to both oscillators to render either alone or both simultaneously effective upon said applicator circuit to cause said circuit to deliver either damped or undamped waves or a derivative of both types of current.

20 4. An electro-surgical apparatus comprising a vacuum tube oscillator circuit, a spark gap oscillator circuit, each said oscillator circuit having an output circuit, the output circuits including a common applicator branch electrically connected with respect to each said oscillator circuit in parallel with the output circuit of the other oscillator circuit and switch means whereby a source of energy may be selectively connected to either and to both oscillator circuits to render 25 either alone or both simultaneously effective upon said common applicator branch, said oscillator circuits including means for causing substantially all of the energy derived from each said oscillator circuit to be delivered to said applicator branch.

35 5. An electro-surgical apparatus comprising an electro-surgical applicator circuit, a spark gap oscillator circuit and a vacuum tube oscillator circuit, said circuits being connected in parallel and including means for causing substantially all of 40 the energy derived from each said oscillator circuit to be supplied to said applicator circuit.

6. In electro-surgical apparatus having a source of high frequency cutting energy, a source of high frequency coagulating energy conjointly operable with the said source of high frequency cutting energy, a ground electrode, and an applicator electrode, means electrically connecting said sources of energy in parallel and to said electrodes, and means associated with each said source of 45 energy for causing substantially all of the energy from the other said source of energy to be delivered to said applicator and ground electrodes.

7. An electro-surgical apparatus comprising a vacuum tube oscillator, a spark gap oscillator, each said oscillator having an output circuit, said output circuits including a common applicator branch electrically connected with respect to each oscillator in parallel with the other oscillator.

55 8. An electro-surgical apparatus comprising a vacuum tube oscillator output circuit, a spark gap oscillator output circuit, each oscillator output circuit including means of low impedance for its own energy and of high impedance for the energy of the other oscillator output circuit, an applicator circuit, a coupling connecting the oscillator output circuits in parallel relation to each other and both to the applicator circuit, and means for varying the energy either oscillator output circuit may impart to the applicator circuit.

60 9. An electro-surgical apparatus comprising a damped-wave-current output circuit, an undamped-wave-current output circuit, each output circuit including means of low impedance for its own energy and of high impedance for the energy

of the other circuit, an applicator circuit, a coupling connecting the output circuits in parallel relation to each other and both to the applicator circuit, and means for varying the energy either output circuit may impart to the applicator circuit.

5 10. An electro-surgical apparatus comprising a vacuum tube oscillator output circuit, a spark gap oscillator output circuit, an applicator circuit, a coupling connecting the oscillator output circuits in parallel relation to each other and both to the applicator circuit, and means associated with each oscillator output circuit for varying the energy such oscillator output circuit may impart to the applicator circuit.

15 11. An electro-surgical apparatus comprising a vacuum tube oscillator output circuit, a spark gap oscillator output circuit, an applicator circuit, a coupling connecting the oscillator output circuits in parallel relation to each other independently of the applicator circuit and both to the applicator circuit, and means associated with each oscillator output circuit for varying the energy such oscillator output circuit may impart to the applicator circuit.

20 12. An electro-surgical apparatus comprising a vacuum tube oscillator output circuit, a spark gap oscillator output circuit, each oscillator output circuit including means for opposing the flow therethrough of energy from the other oscillator output circuit, an applicator circuit, a coupling connecting the oscillator output circuits in parallel relation to each other and both to the applicator circuit, and means for varying the energy either oscillator output circuit may impart to the applicator circuit.

25 13. An electro-surgical apparatus comprising an oscillator for producing energy of a predominantly cutting characteristic and having an output circuit, an oscillator for producing energy of a predominantly coagulating characteristic and having an output circuit, each output circuit including means of low impedance for its own energy and of high impedance for the energy of the other output circuit, an applicator circuit, a coupling connecting said oscillator output circuits in parallel relation to each other and both to the applicator circuit, and means associated with the oscillators for varying the energy imparted thereby to the applicator circuit.

30 14. An electro-surgical apparatus comprising a source of damped current waves, a source of undamped current waves, an electro-surgical applicator, and coupling means having a common electrical terminal at ground potential with said electro-surgical applicator and each said source of current waves, said coupling means, said electro-surgical applicator, and each said source of current waves respectively having other terminals conductively related to each other and at potentials different from the potential of said common terminal.

35 15. In an electro-surgical apparatus including a pair of oscillators capable of producing damped and undamped electrical oscillations, the combination of an applicator electrically associated with both oscillators, for deriving energy therefrom, with means in the output from each said oscillator electrically associated with said applicator, for maintaining a predetermined ratio between the amounts of energy derived from said oscillators by said applicator.
